WILLIAM G. THEOBALD, OF ARCHBOLD, OHIO

IRONING BOARD

Application filed September 12, 1928. Serial No. 305,587.

My present invention has reference to an improved collapsible ironing board and my primary object is the provision of a board of this character which may be set up to produce a strong and efficient structure in an easy and expeditious manner and which likewise may be easily and quickly folded or collapsed.

To the attainment of the foregoing the invention consists in the improvement herein-
10 after described and definitely claimed.

In the drawings:

Figure 1 is a side elevation of the improve-
ment in operative position.

Figure 2 is a bottom plan view thereof in
15 collapsed position.

Figure 3 is a detail perspective view.

Referring now to the drawings in detail, the numeral 1 designates the board which is of the ordinary size and wooden construction.
20 The board, adjacent to its rear end is pro-
vided with a transverse strip which termi-
nates away from its edges and to the ends of
this strip there are pivoted legs 3 that provide
one of the props of the improvement. The
25 spaced legs 3 are connected by cross braces 4.
The legs 3 receive therebetween and have
pivoted thereto, as at 5, other and shorter
legs 6 which provide the second prop for the
board. The spaced legs 6 have also connected
30 thereto cross braces 7. The braces 4 and 7 are
arranged below or outward of the pivot 5.
The legs constituting the prop 6 have one of
their edges beveled, as at 8, and these notches
are designed, when the device is in set up con-
35 dition, to engage with the shouldered portion
9 of a strip or cleat 10. The cleat has its outer
face beveled, as at 11, the purpose of which
will presently be described.

The legs constituting the prop 6 are con-
40 nected by a round 12 and this round is re-
ceived in a slot 13 of a longitudinally extend-
ing guide 14 whose ends are fixed to the under
face of the board 1. The slot 13, has its outer
wall, at the portion thereof above the cleat 10
45 deepened, that is, the inner face of the outer
member of the guide is depressed or notched,
as at 15. This reduced portion 15 of the outer
element of the guide is naturally of a quicker
resiliency than the remainder of the said outer
50 portion of the guide. When in set up position

the notched ends of the legs constituting the prop 6 engage the shoulder 9 of the cleat 10. By merely exerting a pressure upon the rear of the board, the said board will be tilted to bring the notches out of engagement with the shoulder and to permit the angle ends of the legs 6 gliding over the angle surface 11 of the cleat 10 so that the legs may be easily and quickly folded against the under face of the board. The board may be set up in operative 55 position by reversing this operation or by an outward pressure upon the outer end of the said board, although, of course, the legs may be swung by folding the same together to bring the same to board-supporting position. The round 12 being guided through the slot 13 of the guide 14 positively ar-
ranges the notched ends of the legs 6 for proper engagement with the cleat 10. When so arranged the reduced or notched portion 60 65 70 75 80 85 90 95 100

Having described the invention, I claim:

An ironing board having a transverse cleat on the under face thereof adjacent to one of its ends, a guide fixed on the under face of the board arranged over the cleat and having its outer wall reduced to add to the resiliency thereof, a pair of legs hinged to the under face of the board, prop legs pivotally secured to the first mentioned legs and having notched ends to engage the cleat, and a round connecting 90 95 100 said legs passing thru the guide and frictionally engaging the reduced and resilient portion of the guide when the board is in set up position.

In testimony whereof I affix my signature.

WILLIAM G. THEOBALD.
